UNITED STATES PATENT OFFICE.

LAWRENCE E. ROBINSON, OF COFFEYVILLE, KANSAS.

SEPARABLE RETAINING MEMBER FOR WELL-PACKERS.

1,094,021.

Specification of Letters Patent.

Patented Apr. 21, 1914.

Application filed May 26, 1913. Serial No. 770,042.

To all whom it may concern:

Be it known that I, LAWRENCE E. ROBINSON, a citizen of the United States, residing at Coffeyville, in the county of Montgomery and State of Kansas, have invented certain new and useful Improvements in Separable Retaining Members for Well-Packers, of which the following is a specification, reference being had therein to the accompanying drawing.

This invention relates to certain new and useful improvements in separable retaining members for well packers for holding the telescoping sections apart until the desired depth has been reached; the object being to provide a retaining member formed of two sections so connected that they can be easily separated by dropping a sinker bar or bailer down into the well in order to strike the separable member a blow.

Another object of the invention is to provide a device which is exceedingly simple and cheap in construction and one in which the two separable members are held together by a bolt.

Another and further object of the invention is to provide a washing connection with separable members provided with side flanges in order to prevent the sections from twisting by side stress.

Other and further objects and advantages of the invention will be herinafter set forth and the novel features thereof defined by the appended claims.

In the drawings Figure 1, is a side elevation of my improved separable retaining member showing the application of the same to a well between the telescoping sections; Fig. 2, is a horizontal section taken on the line 2-2 of Fig. 1; Fig. 3, is a perspective of the separable member detached from the well; Fig. 4, is a perspective of the separable member showing the parts thereof separated; and Fig. 5, is a perspective view of the flange washer and nut, detached.

Like numerals of reference refer to like parts in the several figures of the drawings.

In the drawings, 1 indicates the lower section and 2 the upper section of a well casing; the two sections being arranged to telescope each other; the upper section 2 being provided with the usual form of packing 3. Oppositely disposed slots are formed in the upper section 2 to receive my improved separable retaining member 4 in order to pre-

vent the same telescoping into the lower section, and as herein shown, I connect the same by rivets but it is of course understood that the separable member is adapted to be used in connection with a telescoping casing without the use of rivets. The separable member 4 is formed of a pair of duplicate sections 5 and 6 provided with reduced rounded ends which extend through the slots as clearly shown in Fig. 1. The abutting ends 65 of the sections 5 and 6 are vertically grooved as shown at 5' and 6' to receive a clamping bolt 7 which carries a washer 8 adjacent the head thereof and passes through a flange washer 9 which straddles the sections 5 and 6 as shown in Fig. 3 and is adapted to be secured in position thereon by a nut 10.

In assembling the retaining member, the members are placed in alignment with each other, until the grooves formed in the abutting ends form a bore to receive the bolt 7 and the flange washer 9 is placed on the bolt until the flanges thereof extend up alongside of the sections and the nut 10 is then screwed into position upon the bolt so as to securely 80 clamp the sections 5 and 6 to form a complete member which can be readily inserted in position between the telescoping sections of the well casing.

When the separable member is in the position shown in Fig. 1 within a well casing by the peculiar shape of the clamping washers, it will resist upward pressure but will yield by being struck a blow with a bailer in order to force the reduced ends of the 90 sections out of the slots as the two sections are separated by the pressure brought to bear thereon.

From the foregoing description, it will be seen that I have provided a separable retaining member which is formed of two sections clamped together in such a manner that they will readily separate in order to move the sections out of the slots of the well casing; the flange washer holding the sections 100 together until they have been practically forced out of the slots.

I claim:

1. A separable sectional retaining member for well packers, comprising a pair of 105 sections having abutting ends, and means for clamping said sections together for preventing movement of said sections in respect to each other in one direction.

2. A separable retaining member for well 110

packers comprising a pair of sections arranged end to end having means for clamping the sections together.

3. A separable retaining member for well packers comprising a pair of duplicate members having grooved abutting ends, and a bolt arranged within the grooves of said ends for clamping said members together.

4. A separable retaining member for well packers comprising a pair of members arranged in alinement, each member being provided with a reduced outer end, and a grooved inner end, a bolt arranged between the grooved ends of said members, a washer carried by said bolt resting upon the upper edge of said members, and a flange washer arranged on said bolt embracing the sides of said members.

5. A separable retaining member for well packers comprising a pair of duplicate sections having grooved abutting ends, a bolt arranged in the grooves of said ends, a

flange washer arranged in said bolt extending up alongside of said sections, and a nut mounted on said bolt for clamping said sections together. 25

6. A retaining member for well packers, comprising a pair of abutting sections detachably connected together, a bolt for clamping said sections at their abutting ends, and means for preventing said sections from moving in respect to each other in one direction. 30

7. A separable retaining member for well packers, comprising a pair of abutting sections detachably secured together for preventing movement in one direction. 35

In testimony whereof I affix my signature in presence of two witnesses.

LAWRENCE E. ROBINSON.
